UNITED STATES PATENT OFFICE.

GEORGE SABO, OF PHILADELPHIA, PENNSYLVANIA.

BENCH OR HAND PLANE.

1,146,525.

Specification of Letters Patent. Patented July 13, 1915.

Application filed February 19, 1915. Serial No. 9,227.

To all whom it may concern:

Be it known that I, GEORGE SABO, a subject of the Emperor of Austria-Hungary, but now residing at the city of Philadelphia, in the county of Philadelphia and State of Pennsylvania, have invented certain new and useful Improvements in Bench or Hand Planes, of which the following is a specification.

The principal object of my invention is to provide a bench or hand plane in which the character of the work performed is maintained uniform indefinitely due to the manner in which the blade can be adjusted within the transverse slot of the block and to compensate for increase in the size of the slot due to wear of the working surface of the block.

My invention stated in general terms, consists of a bench or hand plane constructively arranged in substantially the manner hereinafter described and claimed.

The nature, scope and characteristic features of my present invention will be more fully understood from the following description taken in connection with the accompanying drawings forming part hereof, in which—

Figure 1, is a side elevational view of a bench or hand plane of my invention. Fig. 2, is a vertical longitudinal sectional view through the plane, certain of the parts being shown in elevation. Fig. 3, is a top or plan view of the plane. Fig. 4, is a front end view of said plane. Fig. 5, is a vertical sectional view on the line 5, 5, of Fig. 2. Fig. 6, is a diagrammatic view, showing the relative positions of the blade with respect to the shiftable section of the block, due to wear of the working surface of said block; and Fig. 7, is a perspective view of a key for tightening the heads to the centrally arranged angular bolt extending through the fore-part of the shiftable section of said block.

Referring to the drawings a , is the oblong block provided with a rear inclining depression a^1 , forming a bearing for a plate a^2 , carrying a threaded sleeve a^3 , of a take-up device a^4 , for a slotted and inclined blade b . In the slot b^1 of the said blade b , is mounted a stud b^2 , of a cap b^3 . This cap is provided with a right angular upper perforated extension b^5 , embracing the stem of the screw a^6 , as clearly shown in Fig. 2, whereby the blade b , may be shifted, to vary the cutting

edge within the slot a^6 , with respect to the working surface of the said plane. The lower portion of the blade b and cap b^3 , are held in operative relationship by a tightening bolt b^6 and clamp b^7 , the latter having a locking cam b^8 , with a spring b^9 , as clearly shown in Fig. 2. The blade b , along one edge as illustrated in Fig. 1, is provided with a scale.

It is important that the slot a^6 , should be maintained always practically uniform in size or dimension for insuring the free release of the shavings from the article being planed, without regard to wear of the bottom a^5 , due to constant use of the plane. In this connection and to provide therefor, the front of the block of the plane a , is made with a shiftable section a^7 , slidable in ways a^8 , provided in the respective walls of the said block a . The section a^7 , is slotted at a^9 , a^{10} , a^{11} , and a^{12} , respectively and through which are inserted cross-bolts a^{13} , a^{14} , a^{15} and a^{16} . Certain of the said bolts a^{13} , a^{14} and a^{15} , are tightening means for the said section a^7 when shifted to prevent displacement after the required position of the said section has been arrived at to define the requisite size of the transverse slot a^6 , in which the blade b and cap b^3 , are mounted for the particular planing operations. The bolt a^{16} , is of a square cross-section clearly shown in Fig. 2, has extending into it a longitudinal bolt a^{17} , from the front of the said section a^7 , carrying the hand-hold a^{18} . Surrounding the head of the bolt a^{17} , is a perforated saddle a^{20} , as clearly shown in Figs. 1, 2, 3 and 4, and through the perforation of said saddle a^{20} , a tool can be inserted for turning the said bolt a^{17} , and thereby moving the said section either farther into the transverse slot a^6 , to reduce the size thereof with respect to the blade b and cap b^3 , in position therein or vice versa. The angular cross-bolt a^{16} , is provided on the respective ends with tightening or headed jam nuts operated preferably by a key a^{21} , as clearly illustrated in Fig. 7. The front lower portion of the shiftable section a^7 , is provided with a step-like formation to determine therefrom at a glance, the extent of wear of the bottom a^5 , of the said plane a , from time to time due to use thereof, and just how far such wear can be further permitted by the said step-like formation, without affecting the operative elements of the said section with respect to the said block and also what adjust-

nent of blades in the said transverse slot will be required thereby, to restore the plane to effective working condition.

In Fig. 6, the diagram illustrates in full and dotted outline in the wear of the bottom of the said plane the extent of increase in size if the transverse slot incident thereto and the relative position of the blade *b*, due to such wear and hence to what extent the section *a⁶*, with its step-like formation must be shifted inward in the said block *a*, as well as the blade *b*, elevated to restore the plane again to a relatively operative position for uniform work being derived therefrom.

Having thus described the nature and objects of my invention, what I claim as new and desire to secure by Letters Patent is:—

In combination, a plane having a mouth-piece section provided with an upper oblong

slot having a cross-bolt mounted therein, 20 lower oblong slots having cross-bolts mounted therein and an intermediate slot having a square-bar mounted therein, tightening means on both ends thereof, a longitudinal bolt connected with said square bar, the head of said bolt operable from the front end of the plane and said upper and lower bolts having tightening means connected therewith and operable from the sides of said plane, substantially as and for the purposes described.

In witness whereof, I have hereunto set my signature in the presence of the two subscribing witnesses.

GEORGE SABO.
